Allen J. Hathaway, Alma, Mich., assignor to
William H. Redman, doing business as Alma
Trailer Company, Alma, Mich.

Application December 28, 1935, Serial No. 60,317

Term of patent 7 years

To all whom it may concern:

Be it known that I, Allen J. Hathaway, a citizen of the United States and residing at Alma, in the county of Gratiot and State of Michigan, have invented a certain new, original, and ornamental Design for Trailers, of which the following is a specification, reference being had to the accompanying drawing, forming a part thereof.

In the drawing—

Fig. 1 is a side elevational view.

Fig. 2 is a similar view of the opposite side.

Fig. 3 is a front view.

What I claim is:

The ornamental design for a trailer, as shown.

ALLEN J. HATHAWAY.
